ADJUSTABLE POCKET STEREOSCOPE

Harrison C. Ryker, Oakland, Calif.

Application September 16, 1940, Serial No. 356,920

10 Claims. (Cl. 88—29).

The invention relates to stereoscopes and more particularly to that type of portable stereoscope used for viewing of vertical aerial photographs and the like.

5 An object of the present invention is to provide a stereoscope of the character described which is composed of a stereoscopic eye-piece and a foldable support therefor adapted for mounting on a table or other surface for supporting stereoscopic pictures and which will provide for a simple and ready adjustment of the eye-piece to conform to the individual pupillary spacing of the eyes of the viewer and which may be quickly and easily adjusted for individual eye 10 focus and for proper image definition.

Another object of the invention is to provide a stereoscope of the character above which is composed of a minimum number of sturdily formed parts and so designed and arranged as 15 to fold into substantially flat form of minimum compact size and be of relatively light weight to permit easy portability and roughest type of field use.

Still another object of the invention is to provide an improved type of folding support for a stereoscope of the character described which will have a minimum width so as to provide maximum compactness and yet at the same time will provide firm support for the eye-piece in all 20 pupillary adjustments thereof and with the maximum firmness of support in its normal position.

The invention possesses other objects and features of advantage, some of which, with the foregoing, will be set forth in the following description of the preferred form of the invention which is illustrated in the drawings accompanying and forming part of the specification. It is to be understood, however, that variations in the showing may be adopted within the scope of the 25 invention as set forth in the claims.

Referring to said drawings:

Figure 1 is a plan view of a stereoscope constructed in accordance with the present invention.

45 Figure 2 is a front elevation of the stereoscope illustrated in Figure 1.

Figure 3 is an end elevation of the stereoscope.

Figure 4 is a plan view of the stereoscope similar to Figure 1, but on a reduced scale showing 50 a wide pupillary spacing of the eye-piece.

Figure 5 is a plan view similar to Figure 4, but showing a small or narrow pupillary spacing of the eye-piece.

Figure 6 is a plan view of a modified form of the stereoscope.

Figure 7 is a front elevation of the stereoscope illustrated in Figure 6.

Figure 8 is a plan view of a further modified form of the stereoscope.

With reference more specifically to the accompanying drawings, the stereoscope of the present invention comprises an eye-piece assembly 6 composed of a pair of lens holding members or sections 7 and 8, which in the present instance are of relatively elongated form and are provided with lens barrels or mountings 9 and 11 adjacent arm portions or flanges 12 and 13 of the sections. Means is here provided for pivotally attaching the opposite arm portions 14 and 16 of the sections so as to permit and confine movement of the sections in a substantially common plane and about the axis of the pivotal connection, which in the present construction is spaced from and parallel to the optic axes 17 and 18 of the lenses so as to afford adjustment of the spacing between these axes to conform to various pupillary spacings of the eyes of the users of the stereoscope. Mounted in the lens mountings or barrels 9 and 11 are lenses 19 and 21 which in accordance with the present construction, are of spherical plano-convex type so as to minimize image distortion and to permit rotation of the lens about the pivotal means aforementioned without introducing any prismatic distortion. Any suitable pivotal construction may be used at the arms 14 and 16 of the sections and as here shown, I fasten these ends together by means of a pivotal screw 22.

As will be noted from Figure 1, the pivotal connection 22 for the sections is positioned generally between the optic axes 17 and 18 of the lenses and the sections 7 and 8 are of a length and construction whereby the sections diverge forwardly from the pivot 22 in the normal pupillary spacing of the lenses, so as to define an opening between the sections and the pivot for receipt of the bridge portion of the nose of the user.

The eye-piece is adapted for mounting as aforementioned in elevated position over a picture supporting surface 29, such as a table or desk or the like, and in accordance with the present construction a supporting means is attached to the eye-piece which may be folded from a compact foldable position against the eye-piece into a depending position therefrom for supporting the eye-piece. As will be clear from the accompanying drawings, I attach to the sections 7 and 8 adjacent the flanges 12 and 13 thereof, pivotal supporting members 31 and 55

32. In the present instance the members 31 and 32 are each composed of a generally U-shaped member having a pair of spaced substantially parallel legs 33 and 34, and an intermediate connecting portion having a section 36 thereof disposed at right angles to the length of the legs 33 and 34 and a section 37 which is oblique to the leg 33 and connects this leg with the straight section 36. The intermediate section 36 of the member is pivotally fastened to the under-side of the sections 7 and 8 by means of a bearing clamp 38 and is secured so that the pivotal axis of the member is substantially perpendicular to a line 26 intersecting the lens centers, thereby incidentally also disposing the legs 33 and 34 parallel to the forward edges 23 and 24 of the sections. In this manner, when the eye-piece is adjusted for normal pupillary spacing, as illustrated in Figure 1, the legs set square with respect to the instrument, that is, the legs are parallel to each other and parallel to the line 26. In this normal position of adjustment, the supporting ends of the legs are substantially equally spaced on opposite sides of a transverse plane through the center of gravity of the eye-piece and parallel to the lens axes to provide a maximum firmness of support. It is important to note that with the above arrangement the adjusted setting of the stereoscope with both legs "square" relative to the eye-piece assembly (in which position the firmest support is provided) is also the setting for normal or mean human pupillary spacing; and that in said setting the pivot 22 is offset relative to the line 26 between the lens centers; so that the lens axes lie neither at their position of greatest separation nor of closest approach, but at a setting approximately midway between these extremes. Thus, in adjusting the instrument to accommodate pupillary spacings of individual users, the "zero-point" or point of origin for such adjustments is the "normal" pupillary setting, and the setting of firmest support as well. In this way a relatively large range of adjustment is had with the least possible movement out of the normal setting; and accordingly this range of adjustment is obtained with the least possible loss of firm support. Obviously the vast majority of users will have pupillary spacings deviating only slightly from the normal or mean; and thus, for such users, the deviation from "normal" setting will be so slight that firmness of support of the legs is for all practical purposes unimpaired.

The afore-described arrangement of the legs also facilitates the easy detection of the adjustment of the instrument and indicates at once to the user whether the eye-piece is set for a narrow, normal or wide lens spacing.

By particular reference to the drawings, it will be seen that in a wide lens spacing, as illustrated in Figure 4, the legs diverge rearwardly while in a narrow spacing of the lenses, as illustrated in Figure 5, the legs diverge forwardly. In either instance the spacing between the legs 33 and 34 relative to the center of gravity of the instrument is such as to always provide a firm and steady stance for the eye-piece throughout the entire usual adjustable length of the eye-piece, and as aforementioned with the greatest support provided in and adjacent to the normal pupillary spacing of the lenses. It will further be noted that the spacing between the legs 33 and 34 is somewhat greater than the fore and aft dimension of the eye-piece in the normal pupillary adjustment thereof, as illus-

trated in Figure 1. Accordingly, in folding the legs into the plane of the eye-piece, the legs will surround and embrace the eye-piece so as to provide a compact folded construction of minimum size. In this connection it will also be noted that the beveled or inclined part 37 of the supporting member has approximately the same direction of length when folded as the rearwardly converging rearward edges 39 and 41 of the sections 7 and 8, whereby the supporting legs when folded generally conform to the peripheral shape of the eye-piece. This relationship of the eye-piece and folded legs is shown in dotted lines in Figure 1. In order to further provide a compact arrangement of the stereoscope when folded into horizontal position as aforementioned, I prefer to offset the pivotal connections for the supporting legs from the plane of the sections by a distance permitting a direct superimposing of one of the legs upon the other. This feature will be seen with reference to Figure 2 wherein the pivotal support for the member 31 is arranged slightly higher on the eye-piece than is the pivotal support for the member 32, the difference in elevation of these pivotal supports being at least equal to the diameter of the supporting legs, whereby the member 31 will fold up under the member 32 and in parallel relation therewith.

In using the stereoscope, the supporting legs are folded downward from the eye-piece and rested upon a table or other supporting surface for stereoscopic pictures. At a glance the user will note whether the pupillary spacing of the eye-piece is wide, narrow or normal and make any necessary adjustment for his own eyes. The supporting members 31 and 32 may then be adjusted to properly regulate the height of the eye-piece from the pictures being viewed and frequently some slight additional adjustment of the lenses is necessary to control the slight bowl-shaped distortion usually common to all simple-lens images. Such adjustment may be readily effected in the present instance by slowly moving the pupillary adjustment inwardly while viewing the pictures stereoscopically. Any slightly concave image will be seen to gradually become convex upon such adjustment and a position of adjustment may be found where the image is substantially flat. Once set, the instrument will retain its adjustment unless deliberately changed by another user, or folded up.

In Figures 6 and 7 I have illustrated a somewhat modified form of the invention. In this embodiment, the sections or members 7' and 8' are not only connected together by means of the pivot screw 22', but are by the latter pivotally attached to what may be conveniently termed an attaching or linking member 51. Support for the eye-piece assembly is provided by legs 31' and 32' similar in function and operation to the legs 31 and 32, but secured to the ends of the member 51 instead of to the sections or members as in the first described embodiment. As will be clear from Figure 6, in which the members 7' and 8' are positioned for normal pupillary separation, said members are so arranged that they may be readily adjusted for varying the pupillary separation to the requirements of the user, and that a large range of adjustments is permitted both for increased and decreased separation with respect to normal, without removing from between the free ends of each set of the supporting legs, the plane defined by the lens axes.

In Figure 8, is illustrated a slight modification of the form of the invention shown in Figures 6 and 7. In this embodiment the lens holding members 7" and 8", instead of having a common pivotal connection, are independently pivotally secured to the link member 51 by screws 52 and 53 respectively, which are spaced transversely of each other along the link. With this form of the invention the distance between the lens centers and the pivotal axes may be shorter, so that movement of the members may be more directly opposed in adjusting the device.

I claim:

1. A flat-folding pocket stereoscope comprising:—an eyepiece assembly including two lens-holding members, lenses carried thereby, pivotal connection means for said members spaced from the axes of said lenses and providing pivotal movement of said members in a common plane perpendicular to the lens axes to afford accommodation to the pupillary spacings of individual users; and support means for said eyepiece assembly including a plurality of legs pivotally attached to said eyepiece assembly and foldable to an operative position depending therefrom for supporting said eyepiece assembly above a table or the like with said plane in substantially parallel relation thereto and with the lens axes substantially perpendicular thereto; the pivotal attachment of said legs to said assembly providing a folding of said legs to an inoperative position with said legs positioned adjacent and parallel to said common plane of pupillary adjustment.

2. A flat-folding pocket stereoscope comprising:—an eyepiece assembly including two lens-holding members, lenses carried thereby, and means providing a pivotal connection for each of said members for movement in a substantially common plane perpendicular to both lens axes to afford accommodation to the pupillary spacings of individual users; and supporting means including a pair of support units pivotally attached adjacent opposite ends of said eyepiece assembly and rotatable to an operative position depending from said eyepiece assembly wherein said eyepiece assembly may be held above a flat supporting surface with both lens axes substantially perpendicular to said surface; said support units and pivotal attachment thereof to said assembly being so constructed and arranged to permit rotation of said units to an inoperative position wherein substantially all portions of said support units lie substantially at the common plane of pupillary adjustment, each of said support units having at least two support points to engage the flat supporting surface when in operative position, and one pivotal portion attached to said eyepiece assembly as aforesaid, all of said support points in each unit defining a line parallel to the pivotal portion of said unit.

3. A flat-folding pocket stereoscope comprising:—an eyepiece assembly including two elongated lens-holding members pivotally linked adjacent an end of each member to provide pupillary adjustment of the members in a common plane, lenses carried by said members and mounted with their viewing axes perpendicular to said plane; and a pair of supporting members, each including at least two support points and a pivotal portion, means journaling said pivotal portions adjacent the opposite ends of said first members, said support points defining a line parallel to said pivotal portion; said supporting members being radially adjustable about said

means either to an operative position wherein they depend transversely therefrom to provide support for said eyepiece assembly over a flat surface with the lens axes substantially perpendicular thereto, or to an inoperative position wherein they lie flat in proximate relation with the common plane of pupillary adjustment.

4. A flat-folding pocket stereoscope comprising:—an eyepiece assembly including two lens-holding members pivotally linked in spaced relation to their viewing axes to provide pupillary adjustment between the members in a common plane perpendicular to said axes; a pair of supporting members, each including at least two support points and a pivotal portion, said support points defining a line parallel to said pivotal portion; and means pivotally attaching said portions adjacent opposite ends of said eyepiece assembly for rotatable movement of said supporting points to a plurality of positions spaced from said eyepiece assembly to support the latter at different elevations over a flat surface with the lens axes substantially perpendicular to said surface.

5. A flat-folding pocket stereoscope comprising:—an eyepiece assembly including two lens-holding members and a linking member, said lens-holding members being pivotally connected to said linking member to provide oscillatory movement of said first members in a common plane perpendicular to the lens axes to permit adjustment to the pupillary spacing of individual users; and supporting means including support units pivotally attached adjacent opposite ends of said linking member and rotatable to an operative position depending from said eyepiece assembly for supporting the latter above a flat supporting surface with said lens axes substantially perpendicular thereto, and rotatable to an inoperative position wherein said support units lie substantially in their entirety in substantially the common plane of pupillary adjustment.

6. A flat-folding pocket stereoscope comprising:—an eyepiece assembly including two lens-holding members and a linking member, means independently pivotally connecting said lens holding members to said linking member and providing relative movement between said lens holding members in a common plane perpendicular to the lens axes to permit accommodation to the pupillary spacing of individual users; and supporting means including a pair of support units pivotally attached adjacent opposite ends of said linking member and rotatable outward therefrom to an operative position wherein said eyepiece assembly is held above a flat supporting surface with the lens axes substantially perpendicular thereto, or rotated into an inoperative position wherein said support units lie substantially in the common plane of pupillary adjustment.

7. A flat-folding pocket stereoscope comprising: an eyepiece assembly including two lens-holding members and a linking member, means independently connecting said lens-holding members to said linking member to afford relative movement of the former in a common plane perpendicular to the lens axes to permit accommodation to the pupillary spacing of individual users; and supporting means including supporting units connected to said linking member adjacent opposite ends thereof and adjustable to support the linking member at different elevations from a supporting surface.

8. A flat-folding pocket stereoscope comprising:—a pair of lens-holding members, lenses

carried by said members, means pivotally joining said members for movement in a common plane about an axis positioned between, and parallel to the optic axes of said lenses to afford adjustment 5 of the spacing between said optic axes to conform to the pupillary spacings of individual users; said members and means being so constructed and arranged to position said pivotal axis at one side of a line through the two lens-centers when said 10 members are adjusted for normal pupillary spacing; and a pair of legs pivotally attached adjacent the outer portions of each of said members along axes parallel to said common plane of pupillary adjustment and substantially at right 15 angles to the line through both lens-centers when the latter are adjusted for normal pupillary spacing, said legs being foldable about their axes of attachment from positions substantially in said common plane of adjustment, to positions dependent transversely therefrom and arranged in 20 said latter positions to support said members above a picture-supporting surface with said optic axes substantially perpendicular thereto and with the free ends of each pair of legs spaced on opposite sides of the plane through both optic axes, and defining lines at right angles to the line through both lens-centers when the latter are 25 adjusted for normal pupillary spacing.

9. A flat-folding pocket stereoscope comprising:—a pair of lens-holding members each having an arm and a flange substantially on opposite sides of a lens-holding portion, lenses carried by said portions, said arms being joined pivotally about an axis parallel with the optic axes of 30 said lenses and positioned to one side of a line through both lens-centers when the latter are adjusted for normal pupillary spacing, said members being movable about said pivotal point in a plane perpendicular to the optic axes during adjustment to accommodate the pupillary spacing of individual users; U-shaped supporting legs pivotally attached to said flanges with axes of pivotal attachment parallel to the common plane of 35 pupillary adjustment, said axes being offset one with respect to the other whereby the legs may be swung from transversely dependent operative positions into positions defining closely spaced superimposed planes parallel to the common plane of pupillary adjustment, one leg unit being longer 40 than the other to compensate for the said offset.

relation, thereby permitting support when the legs are in symmetric angular relation to said eyepiece assembly of said lens-holding members above a flat supporting surface with the optic axes substantially perpendicular thereto; the axes of attachment of said legs to said members being so arranged as to be mutually parallel and at right angles to the line through both lens-centers when the latter are adjusted for normal pupillary spacing.

10. A flat-folding pocket stereoscope comprising:—a pair of lens-holding members each having an arm and a flange substantially on opposite sides of a lens-holding portion, lenses carried by said portions, said arms being joined pivotally about an axis parallel with the optic axes of the lenses and positioned to one side of a line through both lens-centers when the latter are adjusted for normal pupillary spacing, said members being movable about said pivotal axis in a 20 plane perpendicular to the optic axes during adjustment to accommodate the pupillary spacing of individual users; U-shaped supporting legs pivotally attached to said flanges with axes of pivotal attachment parallel to the common plane 25 of pupillary adjustment, said axes being offset one with respect to the other whereby the legs may be swung from transversely dependent operative positions into positions defining closely spaced superimposed planes parallel to the common plane of pupillary adjustment, one leg unit being longer 30 than the other to compensate for the said offset.

35 relation to said eye-piece assembly of said lens-holding members above a flat supporting surface with the optic axes substantially perpendicular thereto; the axes of attachment of said legs to said members being so arranged as to be mutually parallel and at right angles to the line through both lens-centers when the latter are adjusted for normal pupillary spacing, the form and arrangement of said legs being such that when folded into inoperative position with said lens-holding members adjusted for normal pupillary 40 spacing the portions of said legs extending from their axes of attachment, will substantially surround and conform to the peripheral shape of the lens-holding members.

HARRISON C. RYKER. 50
